DUPLICATOR

Frederick W. Storck, Arlington, Mass., assignor
to Standard Mailing Machines Company,
Everett, Mass., a corporation of Massachusetts

Application June 19, 1936, Serial No. 86,114

15 Claims. (Cl. 101—132)

This invention relates to an improved and simplified duplicating machine for duplicating and multiplying records or the like by the method in which a record is made on a sheet of paper or the like, in reverse, with suitable dissolvable copying ink and reproduced directly therefrom as positive copies on clear sheets of paper or the like.

In duplicating machines of the character described herein, it is the practice to moisten the clear sheet, on which the duplicate copy is to be imprinted, with a volatile quickly diffusing moistening fluid. Such fluids and compositions of fluids used as activating agents are now known to those skilled in the art. The function of the fluid activating agent is to dissolve a minute but sufficient amount of the ink from the master characters, when the clear moistened sheet is engaged therewith under pressure, to form clear legible duplicates thereof.

To obtain desired and efficient results in duplicating on a previously moistened sheet the matter imprinted in reverse on a master sheet with a suitable copying ink, it is essential to substantially divide the copying ink, forming the master characters, into the number of duplicate copies desired. This desired number of duplicate copies may vary up to 200 or more.

While the character of the copying ink, fluid and paper to be duplicated upon has a direct bearing on the number of duplicate copies obtainable, this is to a minor degree only. The essential requirement is to obtain the maximum number of clear duplicate copies permissible from the particular character of the paper and ink being used. To obtain this desired maximum number of copies, the face of the clear sheet to be duplicated upon must be provided with an extremely limited amount of moisture, that is, the face of the sheet must be uniformly and sufficiently moistened to, when engaged under pressure with the master copy, dissolve only sufficient of the master copying ink to produce a clear sharp copy of the master on the clear sheet. If the face of the sheet to be duplicated upon carries an excess of moisture, when it is engaged with the master copying ink, an excess of ink will be dissolved and deposited on the clear sheet, thus resulting in fewer copies being obtained from the master copy.

In the art of duplicating on a previously moistened sheet the matter imprinted in reverse on a master copy sheet with a suitable dissolvable copying ink, the problem of moistening the sheet to be duplicated upon in a satisfactory manner so as to obtain the above desired and required results has been the object of numerous schemes

and devices. Such devices have been arranged to apply the moisture to the face of the sheet which is engaged directly, under pressure, with the master ink characters. Such a duplicator embodying a moistening device which uniformly applies a limited amount of moisture to the face of the sheet which is to be duplicated upon is illustrated in my U. S. Letters Patent Re. 19,951.

A particular object of my present invention is to provide a so-called wet process duplicator of a simplified and efficient construction that may be manufactured and sold to users of such machines at a reasonably low cost.

Another object of my invention is to so arrange certain elements of my duplicator so as to serve a dual purpose.

A further principal object of my invention is to provide a novel method for supplying moisture to the face of a clear sheet which is to be duplicated upon.

The above objects are stated as a general explanation and should not be construed as limiting my invention thereto, as further objects will be evident in my combination and arrangement of parts hereinafter described and more specifically pointed out in the appended claims.

In accomplishing the objects of my invention, a master is formed in reverse, as is well known, with a suitable dissolvable copying ink and the master suitably attached to a rotatable drum. The clear sheets to be duplicated upon are of a suitable commercial grade having sufficient absorptive qualities to permit a volatile diffusing liquid to quickly penetrate through the sheet body. Various grades of paper of this character are manufactured and sold and are generally known as duplicator paper. Moisture is applied to the face of the sheet opposite to the face which is to receive the duplicate impression and a limited but effective amount of the fluid penetrates to this face, to be duplicated upon, so that when the clear sheet is engaged under pressure with the master ink characters, sufficient ink is dissolved therefrom to make a clear legible duplicate copy on the clear sheet.

In the accompanying drawings I have shown a preferred form of duplicating machine with my improvements embodied therewith sufficient to enable those skilled in the art to understand the construction and operation thereof.

Referring to the drawings:

Fig. 1 is a vertical section of my wet process duplicator and is taken substantially along line 1—1, Fig. 2.

Fig. 2 is a transverse section taken substantially

along line 2—2, Fig. 1; in this view some of the parts are omitted.

Fig. 3 is a fragmentary view of my printing platen or drum and pressure roller as shown at 5 Fig. 1, but shows the pressure roller in a different position.

Figs. 4 and 5 are detail views of my driving gears showing the gears in different relative position.

Fig. 6 is a fragmentary view of my printing platen as shown at Fig. 1, but shows my master 10 copy clamp in a different position.

The duplicating machine

My machine is provided with side frames 10, 11 15 which are retained in spaced relation by suitable main tie rods 12, 13, 14, 15 and 16. These frames 10, 11 support the elements of the duplicator.

The printing platen or drum 17 is preferably of a hollow construction and in this instance is provided with removable end walls 17a, 17b. This drum 17 is effectively secured to a shaft 18 which is rotatably mounted in suitable and preferably anti-friction bearings 19, 20 which are secured in the side frames. Lengthwise movement of the 20 shaft is prevented, in this instance, by means of shoulders 18a, 18b formed in the shaft 18 and which bear against the inner faces of the bearings 19, 20.

The roller 21 functions as a combined pressure 30 and moistening roller and is preferably formed of a resilient substantially non-absorptive material such as rubber or the like. This roller 21 is secured to a shaft 22 which has its ends rotatably mounted in suitable bearings of opposed brackets 35 23, 23 which are, in turn, rotatably supported on the turned down portion of opposed spacer bushings 14a on the rod 14. These brackets 23 are provided with integral depending arms 23a which engage with eccentric locking cams 24, 24 secured 40 to a transverse rod 25 rotatably supported in the side frames 10, 11. This rod 25 is provided with a handle 25a by means of which the rod 25 may be rotated to actuate the cams 24 against the arms 23. These cams 24, as illustrated at Fig. 1, retain 45 the roller 21 in a close pressing engagement with the printing drum 17 and the cams 24 are further utilized for a purpose hereinafter mentioned.

For the purpose of illustration I have shown a preferred form of a device for supplying my intermediate applicator with moisture, but it is obvious that other means may be provided for effectively supplying the moisture and, therefore, my illustrated moistening device is not to be construed as limiting my duplicating machine 55 thereto.

The moistening device

In this illustrated moistening device the moistening fluid is contained in an inverted reservoir 60 26 of suitable construction to hold a desired quantity of the moistening fluid. This reservoir is provided with a depending tube 27 adapted to communicate with an enclosed fluid tank 28 which extends between the side frames 10, 11. This tank 65 28 is secured to a spacing bar 29 adapted for rotation in suitable bearings in the side frames. In this instance the tank 28 is provided, adjacent its top, with a longitudinal slot in which is frictionally disposed a wick 30 that extends into the tank 28 and engages with the fluid therein.

The spacing bar 29 is provided with a depending arm 31 to which is secured one end of a pull spring 32. The opposed end of said pull spring 32 is attached to a fixed stud 33 secured in the tie rod 12. 70 This pull spring 32 causes the outer longitudinal

edge of the wick to engage the peripheral face of the roller with a degree of pressure and the backing plate 33 acts as a stiffener for the roller engaging edge of the wick.

A moistening device of the above character with the functions thereof is fully shown and described in my U. S. Letters Patent No. 2,036,972 and, therefore, further detailed description of this moistening device is thought unnecessary. 5

The master copy clamp

A transverse groove or recess 34 is provided in the peripheral face of the printing drum. This groove 34 is provided with a plurality of slots 35 which connect the groove 34 with the chamber of the drum 17. Disposed in the drum groove 34 and pivotally supported against the bottom thereof and extending longitudinally therein is a substantially ribbon-like clamp member blade 36. This clamp member is provided with extensions 36a 20 which are adapted to project through the communicating slots or apertures 35 and extend into the drum chamber. 25

Each inner end portion of the clamp extensions 36a has secured thereto one end of a spring 37, 30 the opposed ends of said springs 37 being attached to studs 38 which are secured in the drum shell. These springs 37 are preferably disposed in an angular position so as to effect a pivotal seating of the clamp blade 36 against the bottom 35 of the groove or recess 34, together with effecting a resilient pivot for the extensions 36a. The springs urge the extensions 36a to the right, thus causing the intermediate portion of the clamp member to pivot against the bottom of the groove 34 and against the inner edge of the communicating slots 35, thus causing the outer edge portion of the blade 36 to be pressed against the side wall 34c of the recess 34 with sufficient force to retain an edge of a master copy sheet A there- 40 between.

Further, it may be said that the extensions 36a, of the ribbon-like clamp blade 36, act to cause the outer edge portion of the blade 36 to bear with its greatest pressure at a point in a substantially vertical line with the extensions 36a and, in effect, function in the manner of individually controlled contact points or areas as could be effected likewise with a plurality of individual or segmental blades that were each supported in 50 the groove and provided with extensions adapted to function in the manner of the present illustration. 45

In this instance I have provided a cam member 39 which extends longitudinally within the drum 55 and is positioned to be engaged with the clamp extensions 36a. This cam member 39 is rotatably supported in the end walls of the printing drum 17 and is provided with an operating knob 40. When the cam member 39 is rotated, it engages 60 the extensions 36a and flexes the clamp member against its pivots, thereby causing the outer edge of the clamp to be actuated within the groove 34 and away from engagement with the groove wall 34c and thus permits the insertion of an edge 65 of a master copy sheet between the wall 34c and its coacting face of the clamp member blade 36.

The duplicating machine drive

I have arranged and proportioned my duplicator elements so that the same may be operated in synchronism and a definite rhythm established between the feeding and position of a sheet and the rotation of the duplicator elements. In the accomplishment of this desired rhythmical effect, 70 75

in my preferred form, the printing platen 17 is directly proportioned relative to the roller 21. The platen drive shaft 18 has secured thereto a gear 41 which meshes with a pinion secured to the roller shaft 22. In this instance the proportions which I have preferably selected effect a 2 to 1 ratio, that is, the gear 41 and platen 17 make one revolution to two revolutions of the pinion 42 and roller 21. It is obvious that these proportions may be varied to suit circumstances and conditions and retain my desired rhythmical effect. The outer end of the shaft 22 is, in this instance, provided with an operating crank handle 43 and by means of which the duplicator elements are rotated.

To effect a determinate stopping point or position for the printing platen 17, the platen gear 41 is provided with a recess 41a adapted to receive a portion of a lock-ball 44 which is supported in a housing 45 secured to the side frame 10. This ball is resiliently urged into engagement with the inner face of the gear 41 by means of a compression spring 46 which is supported in the ball housing 45. As the gear 41 is rotated, the ball rides on the face thereof until it registers for engagement with the gear recess 41a and the spring 46 forces it into engagement therewith.

Operation of the duplicating machine

30 In preparing the machine for operation, the cam 24 is rotated so as to permit the bracket 23 to swing about its pivot 14 and thus position the roller 21 in a spaced-apart relation relative to the peripheral face of the printing platen 17, see Fig. 3. It is to be noted that, when the roller 21 is spaced apart, the teeth of the gear 41 and pinion 42 are so constructed as to remain in their engaging relation, see Figs. 4 and 5. It is obvious that without this spaced-apart position of the moistening roller 21, moisture would be applied directly to the face of the printing platen 17 or to a master copy sheet secured thereto and, in this last instance, would ruin the master copy.

When the clamp 36 is rotated to a convenient position, the edge of the master copy sheet is clamped as aforesaid with the reverse ink characters on the outer or exposed face of the master copy sheet. The printing platen is then rotated to its determinate stop which is indicated by the 50 yielding lock-ball 44 engaging in the gear recess 41a. The cam 24 is then rotated against the bracket arm 23a and thus causes the roller 21 to engage under pressure with the face of the printing platen. When the printing platen 17 is in its indicated stopped position, the clamp edge of the master copy sheet A is positioned in or close to the bight B formed by the platen 17 and pressure roller 21.

To circumferentially guide the master sheet in 60 relation to the face of the platen and to prevent excessive flopping of the sheet as the platen is rotated, the tie rods 15, 16 have rotatably mounted thereon a plurality of rollers 58 which are retained in longitudinal position by spaced collars 65 secured to the rods 15, 16.

The sheets to be duplicated upon are stacked 70 on a suitable support 52 and fed singly therefrom and positioned in the bight B, formed by the printing platen 17 and roller 21, for registering engagement with the master copy. After positioning the sheet to be duplicated upon, the roller 21 and printing platen 17 are rotated in unison as previously described and, as the roller is rotated, moisture is applied to the face thereof, by 75 the wick 30, and deposited on the face of the clear

sheet opposite to the face of said sheet which is to contact with the master copy and be duplicated upon.

As previously stated, the sheets to be duplicated upon are of a character which permits the volatile quickly diffusing fluid to be readily absorbed thereby and a limited but sufficient amount of the fluid will penetrate to the face of the sheet which is to receive the copy, and this moisture will dissolve sufficient of the ink from the master characters so that when the sheet is simultaneously moistened and advanced under pressure in engagement with the master copy, sufficient of the master character ink will be deposited on the clear sheet to form a clear legible duplicate of the master copy.

As the duplicate copy is advanced through the machine it is guided by a stripper plate 53, which is secured to the tie rod 14, into a suitable receiving receptacle 54.

Having thus described my invention, what I claim is:

1. In a machine for producing on a clear sheet duplicate copies of matter imprinted in reverse on a master sheet and including a fluid activating agent, a frame, a printing platen revolvably mounted in said frame, means for securing a master sheet to said platen, a single combined sheet feeding, moistening and pressure roller adapted for engagement with said platen, means 30 for applying a volatile moistening fluid to said roller to be simultaneously deposited on a sheet of paper substantially as it passes between said roller and platen as it is pressed against said master sheet by said roller, with means for rotating said roller and platen in unison.

2. In a machine for producing on a clear sheet duplicate copies of matter imprinted in reverse on a master sheet and including a fluid activating agent, a frame, a printing platen revolvably mounted in said frame with means for securing a master sheet to said platen, a rotatable combined sheet pressing and moistening roller adapted for engagement with said platen, means for moistening said roller with a volatile quickly diffusing moistening fluid to be simultaneously deposited on a sheet of paper substantially as said sheet is advanced by and between said roller and platen, with means for rotating said roller and platen in unison.

3. In a machine for producing duplicate copies of matter imprinted in reverse on a master sheet, a frame, a printing platen revolvably mounted in said frame, with means for securing a master sheet to said platen, a rotatable combined pressure and moistening roller adapted for engagement with said platen, with means including a wick for supplying a volatile quickly diffusing moistening fluid to the face of said roller to be deposited on a sheet of paper as it passes between 60 said roller and platen, with means for rotating said roller and platen in unison.

4. A machine for producing on a clear sheet duplicate copies of matter imprinted in reverse on a master sheet and including a fluid activating agent, comprising a frame, a printing platen revolvably mounted in said frame with means for securing a master copy to said platen, a pressure roller for said platen with means for applying a volatile quickly diffusing moistening fluid 70 to said roller to be simultaneously deposited on a sheet of paper substantially as it is advanced by and between said roller and platen and pressed against said master by said roller with means for rotating said roller and platen in unison and a 75

support for a stack of sheets to be duplicated upon.

5. A machine for producing on a clear sheet duplicate copies of matter imprinted in reverse on a master sheet and including a fluid activating agent, having a revolvable printing platen and a single combined moistening and pressure roller coating therewith with a determinate positioned stop for said platen and means for applying a volatile quickly diffusing, moistening fluid to said roller to be simultaneously deposited on a sheet of paper substantially as it is advanced by and between said roller and platen, with means for rotating said roller and platen in unison.

6. The method of multiplying copies which comprises forming a master copy in reverse with a dissolvable ink, moistening one face of a sheet to be duplicated upon with a volatile fluid activating agent, disposing the opposed face in engagement with the master copy under pressure.

7. The method of multiplying copies which comprises forming a master copy in reverse with a dissolvable ink, simultaneously moistening one face of a sheet to be duplicated upon with a fluid activating agent and engaging its opposed face under pressure with the master copy.

8. The method of multiplying copies which comprises forming a master copy in reverse with a dissolvable ink, simultaneously moistening one face of a sheet to be duplicated upon with a fluid activating agent and engaging said sheet under pressure with the master copy.

9. In a copy multiplying device having a master copy drum with a chamber therein, a longitudinal recess in the peripheral face of said drum, a resilient clamp member disposed in said recess and having portions thereof pivoted within said drum with means disposed relative to said portions for engagement therewith and whereby said clamp is arcuately flexed and the outer edge portion actuated within said recess.

10. In a copy multiplying device having a master copy drum with a chamber therein, a longitudinal recess in the peripheral face of said drum with apertures communicating with said drum chamber, said apertures being of a less width than said recess to form shoulders, a resilient ribbon-like member disposed in said recess and having portions thereof which extend through said apertures and into said drum chamber, resilient pivotal connections for said portions, rotatable cam means disposed within said drum and adapted to arcuately flex said portions between their pivotal connections and said shoulders and whereby the outer edge portion of said member is actuated within said recess.

11. In a copy multiplying device having a master copy drum with a chamber therein, a longitudinal recess in the peripheral face of said drum with apertures communicating with said drum chamber, said communicating apertures being of a less width than the peripheral face opening of said recess, a clamp member pivoted against the bottom of said recess, said clamp having extensions which project through said apertures and into said drum chamber, resilient pivotal connections for the terminating portions of said extensions, said pivotal connections being

adapted to urge the outer edge portion of said clamp into close engagement with said wall of said recess, with means adapted to engage said extensions and whereby said clamp member is actuated on its recess pivot and its outer edge portion disposed in a spaced relation to said side wall.

12. A machine for producing duplicate copies of matter imprinted in reverse on a master sheet and including a fluid activating agent, having a support for a stack of sheets to be duplicated upon, a revolvable printing platen with means for securing a master sheet thereto, a pressure roller coating with said platen and forming a bight therebetween adapted to receive and position a sheet to be duplicated upon for registering engagement with said master sheet with means including said roller for supplying said positioned sheet with moisture closely adjacent said bight as said sheet is advanced by and between said roller and platen and under pressure in engagement with said master sheet.

13. A machine for producing duplicate copies of matter imprinted in reverse on a master sheet and including a fluid activating agent, having a revolvable printing platen with means for securing a master copy thereto, a combined feeding, pressure and moistening roller adapted for engagement with the peripheral face of said printing platen with means for rotating said roller and platen in unison, and means for supplying said roller with a limited amount of a volatile quickly diffusing fluid to be deposited by said roller on one face of a sheet of paper as it is fed under pressure, by said roller and platen, with its opposed face in engagement with said master copy.

14. A machine for producing duplicate copies of matter imprinted in reverse on a master sheet and including a fluid activating agent, having a revolvable printing platen with means for securing a master copy thereto and a substantially non-absorptive combined feeding, pressure and moistening roller adapted for engagement with the peripheral face of said printing platen with means for rotating said roller and platen in unison, and means for supplying said roller with a limited amount of a volatile quickly diffusing fluid to be deposited by said roller on one face of a sheet of paper as it is fed under pressure, by said roller and platen, with its opposed face in engagement with said master copy.

15. In a copy multiplying device having a master copy drum with a chamber therein, a longitudinal recess in the face of said drum, said recess being of a greater depth than width, apertures disposed between said recess and said drum chamber, a clamp member disposed in said recess, said clamp member being of a less width than said recess and having dependent portions thereof that extend through said apertures and into said drum chamber, resilient pivotal connections for said portions, rotatable cam means disposed within said drum and adapted for engagement with said dependent portions and whereby the outer edge of said clamp is pressed into engagement with a side wall of said recess.

FREDERICK W. STORCK.
